W. F. Bassett
ATTORNEY

UNITED STATES PATENT OFFICE

CARL OTTO, OF ESSEN-RUHR, GERMANY

COKE OVEN

Application filed January 20, 1928, Serial No. 248,235, and in Germany November 16, 1926.

The invention relates to coke ovens, particularly to those having horizontally elongated coking chambers the heating walls of which are subdivided so as to form vertical hairpin flues.

With chamber ovens of this type the brick-work of the heating walls must be able to support the entire weight of the oven cover including the permanent weight of the oven 19 fitting resting on the cover, and the temporary load on the oven cover caused by the door lifting devices and the charging devices travelling on the cover. The heating walls of the chamber ovens of this type substantially consist of two walls parallel to the chamber, the so-called running walls, and of partitions arranged normally transverse thereto, the so-called binding walls, which subdivide the heating walls into the individual heating flues. This brickwork, composed of the running and binding walls, of the heating walls must thus be able to support the above-mentioned load and must therefore have a corresponding total sectional area. 25 Now my invention is based upon the perception of the subdivision of the heating flues into vertical twin flues affording the possibility to take up by said so-called binding walls the entire load of the oven cover including the weights resting thereon, and to thus completely discharge the so-called running walls from the load.

For, as with the arrangement of twin flues each alternate or second binding wall extends 35 throughout the entire height of the heating wall, series of piers or columns may be established within the heating flues by suitably diminishing the sectional area of the binding walls, which piers are able to support the weights entering into consideration.

Referring to the drawings:

Figure 1, is a vertical section of a coke oven on the line 1—1 of Figure 3, showing the decreased thickness of the running walls.

Figure 2, is a longitudinal section on the line 2—2 of Figure 3, and shows the greater thickness of the binder walls with relation to the running walls of Fig. 1.

50 Figure 3, is a horizontal section showing

the relative thicknesses of the binding walls and running walls.

In the drawings the heating walls erected between each pair of horizontally elongated oven chambers (3), each comprise a pair of 55 runner walls (1) which extend in the direction of the oven chamber and a series of transverse binder walls (2) extend between each pair of runner walls. The binder walls are spaced apart in the direction of the oven 60 chamber, and each alternate binding wall of the series extends vertically to the oven cover (5). The binder walls thus provide vertical hairpin flues (4) which extend in a single row in the direction of the chambers. 65

Now, according to my invention and as shown by the drawing, the running walls 1 freed in this way from this load, may be made much weaker than hitherto usual, as they must only have a minimum thickness that depends on the structure itself and on the required resistibility to the stresses occurring for example when the coke cakes are pushed out of the chambers. As the running walls have to form at the same time a gas-tight 70 partition between oven chamber and heating flues, the individual running wall bricks have groove and feather joints, in order to avoid straight joints, as the danger of mutual transitions of gas taking place is naturally much 75 greater with straight joints than with bent joints. This configuration, however, of the bricks having groove and feather joints, of itself provides a minimum thickness of the running walls for construction reasons, this 80 thickness in practice being not less than 65 mm. This thickness is quite sufficient to take up the stresses occurring upon pushing the coke cakes. Of course, account has to be taken 85 of the height of the heating wall. Generally 90 a somewhat greater thickness of the running wall bricks will be provided for with increasing height of the heating wall.

Furthermore account has to be taken of the material of the bricks for the binding and 95 running walls, in particular of the point of fusion of the material. The above-mentioned minimum thickness of 65 mm. holds good of a medium oven height and best silica material having a fusion point lying far above 1550 100

degrees C. In case a very windy coal is to be coked in the chamber oven, this additional stress of the bricks of the running and binding walls must be compensated for by a particularly careful selection of the stone bond and increase of the wall thicknesses. Considering all these factors, a wall thickness of the running walls from 65 to not more than 100 mm. meets all requirements.

10 As each lowering of the thickness of the running walls results in a quicker and better transmission of the heat to the content of the chamber, the great economical importance of the invention is evident, as it not only permits of a large quantity of bricks to be saved, but also of the carbonizing period to be notably shortened.

15 In contradistinction to the decreased runner wall thickness of 65 to 100 mm. to be employed in accordance with my invention (see Figures 1 and 3), the former wall thicknesses of the running walls even of low ovens were generally 130 to 150 mm. and only in special cases 120 mm. Hence a saving of 25 bricks of nearly 50 per cent is obtained by my invention.

20 Although the binding walls have to take up according to my invention the entire weight of the oven cover and the load resting thereon, their thickness generally needs not to be increased, in comparison with the thickness hitherto employed of 130-150 mm. Experience has proved that such, a thickness of the binding wall bricks 2 will serve 30 for the practical realization of my invention. Walls of this thickness have been employed and have even been surpassed in many cases to a considerable extent. This at first sight surprising feature is due to the fact, that 35 the greater part of the former chamber ovens were provided with a horizontal heating passage extending above all the heating flues, and that the binding walls separating the individual heating flues thus did not extend up to the oven cover and thus had to take up only indirectly, through the somewhat projecting running wall bricks that surround said horizontal passage, a certain fraction of the load of the cover 5. By my 40 invention each alternate binding wall 2, extends throughout the entire height of the oven wall to the oven cover (see Figure 2). Each alternate binding wall thus acts as a supporting column for supporting the load 45 of the cover 5. The binding walls always serve as struts for the running walls against the pressures exerted from the oven chambers and must be made rather thick for this purpose. According to the invention this 50 property of the binding walls is fully utilized by a suitable stone bond, and the running wall bricks are discharged as far as possible from this load also.

55 What I claim and desire to secure by Letters Patent is:—

1. In a coke oven having a row of alternate horizontally elongated oven chambers and parallel heating walls therefor arranged side by side, and an oven cover therefor, each of said heating walls comprising a pair of separated runner walls running in the direction of the oven chambers, and a series of parallel faced transverse binder walls extending between each of the pairs of runner walls, the binder walls in each of said series being spaced apart in the direction of the chambers, the alternate binder walls in each of said series extending vertically to the oven cover, and the intermediate binder walls extending to a lesser height providing vertical hairpin flues extending in a row in the direction of the chambers, the binder walls forming the two end faces of the flues; said alternate binder walls constituting supporting columns and being of materially greater thickness than the maximum thickness of the runner walls, so as to support the major part of the weight of the cover and loads resting thereon, and enabling the thickness of the runner walls to be decreased to permit quick transmission of heat, the thickness of the runner walls being sufficient to resist transverse stresses produced in coke pushing.

2. In a coke oven having a row of alternate horizontally elongated oven chambers and heating walls therefor, arranged side by side, and an oven cover therefor, each of said heating walls comprising a pair of separated runner walls running in the direction of the chambers, and a series of parallel faced transverse binder walls extending between each of the pairs of runner walls, the binder walls in each of said series being spaced apart in the direction of the chambers, the alternate binder walls in each of said series extending vertically to the oven cover, and the intermediate binder walls extending to a lesser height, providing vertical hairpin flues extending in a row in the direction of the chambers, the binder walls forming the two end faces of the flues; said alternate binder walls constituting supporting columns and being one and a half to twice as thick as the maximum thickness of the runner walls, so as to support the major part of the weight of the cover and loads resting thereon, and enabling the thickness of the runner walls to be decreased to permit quick transmission of heat, the thickness of the runner walls being sufficient to resist transverse stresses produced in coke pushing.

In testimony whereof, I have signed my name to this specification.

CARL OTTO. 125
